CLAIM

The ornamental design for a display or screen or portion thereof with animated graphical user interface, as shown and described.

DESCRIPTION

FIG. 1 is a front view of a display or screen or portion thereof with a first image of an animated graphical user interface showing our new design; FIG. 2 is a second image thereof; FIG. 3 is a third image thereof; FIG. 4 is a fourth image thereof; FIG. 5 is a fifth image thereof; and, FIG. 6 is a sixth image thereof.

The single dot-dash broken lines defining the boundaries of the claimed design form no part of the claimed design, wherein the areas inside of or between the single dot-dash broken lines are not claimed. The outermost double dot-dash broken lines illustrating portions of the display or screen form no part of the claimed design. The even dash lines within the outermost double dot-dash broken lines illustrating portions of the graphical user interface form no part of the claimed design.

The appearance of the animated graphical user interface sequentially transitions between the images shown in FIGS. 1-6.

The process or period in which an image transitions to another forms no part of the claimed design.

1 Claim, 6 Drawing Sheets
